(57) **CLAIM**

The ornamental design for an indicator strip, as shown and described.

DESCRIPTION

The specification contains at least one drawing executed in color. Copies of the color drawings will be provided by the Office upon request and payment of the necessary fee.

FIG. 1 is a perspective view showing a new design for an indicator strip;

FIG. 2 is a top view thereof;

FIG. 3 is a bottom view thereof;

FIG. 4 is a right view thereof, the left side view being a mirror image thereof;

FIG. 5 is a rear view thereof;

FIG. 6 is a front view thereof;

FIG. 7 is a perspective view showing the new design for an indicator strip;

FIG. 8 is a top view thereof;

FIG. 9 is a bottom view thereof;

FIG. 10 is a right view thereof, the left side view being a mirror image thereof;

FIG. 11 is a rear view thereof; and,

FIG. 12 is a front view thereof.

The broken lines, the areas within them, and the areas adjacent to the shaded areas on the top surface depict portions of the indicator strip that form no part of the claimed design.

1 Claim, 2 Drawing Sheets
